[57] CLAIM

The ornamental design for a reversible sweater, as shown and described.

DESCRIPTION

FIG. 1 is a front elevational view of the reversible sweater of the present invention, the rear elevational view being a mirror image thereof;

FIG. 2 is a left side elevational view of the reversible sweater of FIG. 1, the right side elevational view being a mirror image thereof;

FIG. 3 is a top plan view of the reversible sweater of FIG. 1; and,

FIG. 4 is a bottom plan view of the reversible sweater of FIG. 1.

For convenience of illustration, the wavy horizontal lines on the surface of the invention are understood to represent a texture which continues throughout.
